US00D754238S

(12) **United States Design Patent**
Woodman

(10) **Patent No.:** **US D754,238 S**
(45) **Date of Patent:** **** Apr. 19, 2016**

(54) **CAMERA HOUSING**

- (71) Applicant: **GoPro, Inc.**, San Mateo, CA (US)
(72) Inventor: **Nicholas D. Woodman**, Sausalito, CA (US)
(73) Assignee: **GoPro, Inc.**, San Mateo, CA (US)
(**) Term: **14 Years**
(21) Appl. No.: **29/522,567**
(22) Filed: **Mar. 31, 2015**

Related U.S. Application Data

- (60) Continuation of application No. 29/481,654, filed on Feb. 7, 2014, now Pat. No. Des. 732,593, which is a division of application No. 29/414,593, filed on Feb. 29, 2012, now Pat. No. Des. 702,276, which is a continuation of application No. 13/193,369, filed on Jul. 28, 2011, now Pat. No. 8,150,248, which is a continuation of application No. 12/498,876, filed on Jul. 7, 2009, now Pat. No. 8,014,656.

(57) **CLAIM**

The ornamental design for a camera housing, as shown and described.

DESCRIPTION

FIG. 1 is a front, top and left side perspective view of a camera housing showing my new design;

FIG. 2 is a front, top and right side perspective view thereof; FIG. 3 is a front, bottom and left side perspective view thereof;

FIG. 4 is a front, bottom and right side perspective view thereof;

FIG. 5 is front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines in the drawings showing portions of the camera housing are included for the purpose of illustrating environmental structure and form no part of the claimed design.

1 Claim, 10 Drawing Sheets
